UNITED STATES PATENT OFFICE.

FRANK IORNS GIBBS AND WILLIAM WRIGHT, OF BIRMINGHAM, ENGLAND.

ROLLER-SKATE.

SPECIFICATION forming part of Letters Patent No. 578,081, dated March 2, 1897.

Application filed August 12, 1895. Serial No. 559,065. (No model.) Patented in England December 11, 1894, No. 24,038.

To all whom it may concern:

Be it known that we, FRANK IORNS GIBBS and WILLIAM WRIGHT, subjects of Her Majesty the Queen of Great Britain and Ireland, 5 residing at Birmingham, in the county of Warwick, England, have invented certain new and useful Improvements in Roller-Skates, of which the following is a specification.

The invention has been patented in England, No. 24,038, dated December 11, 1894.

This invention has reference to those pneumatic and other roller-skates which are made with two pneumatic or other rollers under the foot-plate or tread; and the objects of this 15 invention are, first, to so construct the metallic frames of the said skates that they can be made lighter, stronger, and cheaper than heretofore, and, secondly, to afford better means for fixing the said skates to the wearer's feet and for preventing strain on the wearer's ankles.

Our said invention is illustrated by the accompanying drawings, on which—

Figure 1 is a side elevation of a pneumatic 25 or other roller-skate constructed according to this invention. Fig. 2 is a sectional elevation of the same. Fig. 3 is an inverted sectional plan of the same. Fig. 4 is a cross-section through one of the rollers of the same. Fig. 5 is a longitudinal sectional elevation of 30 the frame of the same. Fig. 6 is a plan, and Fig. 7 is a side elevation, of a part of the said metallic frame to illustrate how the same is made; and Figs. 8 and 9 are respectively a 35 plan and elevation of a part of the foot-plate of the said frame. Fig. 10 represents on a smaller scale a sheet-metal blank for forming the part of the frame represented by Figs. 6 and 7. Fig. 11 is another form of the said blank, 40 and Fig. 12 shows a portion of one of the horn-pieces of the said frame separately. Fig. 13 is a side elevation, and Fig. 14 is an inverted sectional plan, of another form of the said metallic frame. Fig. 15 is a cross-sectional 45 elevation of the same, and Fig. 16 shows one of the parts of the same separately, and Fig. 17 shows the metal part of the ankle-support of the said frame separately.

The same letters of reference indicate the 50 same or corresponding parts in all the figures of the drawings.

A is the foot-plate, made with two pairs of

horn-pieces, (marked, respectively, B' B² C' C²,) projecting downwardly and carrying the axles D' D² of the two pneumatic or other rollers 55 or wheels E' E², which are on the longitudinal center line of the skate underneath the foot-plate. The axles D' D² are carried at the proper distance apart and the horn-pieces strengthened by the side stays F' F², extending from one axle D' to the other axle D².

Heretofore the foot-plate A has been usually made of a single piece of sheet metal, which is liable to twist, and the pairs of horn-pieces have also been made of single sheet metal 65 separate from the foot-plate and riveted thereto.

We attain the first object of this invention by making the foot-plate A and the said horn-pieces hollow in any of the several ways, 70 which we will now describe, thereby enabling the skate-frame to be made lighter, stronger, and cheaper than heretofore. According to one method of carrying out this part of our invention (see Figs. 1, 2, 3, 5, 6, 7, 8, 9, 10, 75 11, and 12) we make the upper part A of the foot-plate and the two pairs of horn-pieces B' B² C' C² together from a sheet-metal blank of the corresponding shape and size, such, for instance, as shown on a smaller scale by Fig. 10, the said blank having the shape of the foot-plate A and the halves of the horn-pieces B' B² C' C² standing out from the sides of the same. These halves of the horn-pieces are raised into somewhat of a trough 80 shape in cross-section, as shown in Fig. 3, and bent downwardly at right angles to the foot-plate A, so as to occupy the position shown in Figs. 6 and 7. Each of the half-horns B' B² C' C² is strengthened by a separate half 85 horn-piece G, also made of a trough-section (shown separately by Fig. 12) corresponding therewith and soldered to the halves of the horn-pieces, which are raised with the foot-plate A, so that the completed horns will then 90 be hollow, as shown in Figs. 2 and 3, and very light and strong. The hollow portion of the horns extend almost to the lower ends of the same, these lower ends being flattened and pierced with holes b' c' for the axles D' D² to 95 pass through.

The two tubular stays F' F², which secure the axle ends of the horns at the proper distance apart, may be made separate from the

horns, as at present, or (and this is what we prefer) the said tubular stays $F' F^2$ are raised in a piece with the horn and foot-plate A by cutting out the blank to the proper shape, as shown, for instance, on a reduced scale by Fig. 11, the cross-strips $F' F^2$ connecting the horns, which cross-strips are closed around into the tubular form. Instead of the inner halves G of each of the two horns at either side of the skate being made separate from each other, as above described, and shown in Fig. 12, the two inner parts G for two of the horns at either side of the skate may be formed together with one of the cross-strips $F' F^2$, as shown in Fig. 16, this cross-strip being afterward bent around into the tubular or semi-tubular form, and thus (in combination with the other half of the cross-piece which is formed with the blank, Fig. 11) make the complete cross-stays $F' F^2$; or, as shown in Figs. 13 and 14, the two pairs of horns may be made entirely of four sheet-metal stampings of the hollow shape shown by Fig. 16, each stamping consisting of two half-horns $G' G^2$ and one half of one of the cross-bars $F' F^2$. This will be clear by an examination of Fig. 14, where it will be seen that the four sheet-metal stampings, such as shown by Fig. 16, are marked, respectively, $G' G^2 G^3 G^4$, the meeting edges of each pair of stampings being soldered or otherwise fixed together to form the tubular horn-pieces and cross-stays, as above described. In this case the horn-pieces are by preference fixed to the foot-plate A by the latter being raised with small downwardly-projecting pommels a' , in which the bases of the horns fit and where they are fixed, preferably being soldered therein. The horn-pieces are further strengthened at their bases by the hollow stampings G^5 , which are soldered to the foot-plate A and to the horn-pieces, thus making the frame very strong. We also make the foot-plate A hollow by fixing thereto, preferably on the inside of the same, another plate (marked H) and shown separately by Figs. 8 and 9 of similar shape to the foot-plate A, with the edges h' turned upwardly and soldered or otherwise similarly fixed to the under side of the foot-plate A. This bottom plate H has hollows h^2 in its sides, so as to fit against the rounded hollow horns $B' B^2 C' C^2$. Thus by making the foot-plate A and the horns $B' B^2 C' C^2$ of the inclosed hollow form, as above described, they can be made of very thin metal and yet be very strong.

Instead of making the foot-plate A of thin metal, hollow, as above described, the same may be made of a single piece of metal of increased thickness or corrugated, so as to obtain greater strength.

We obtain the second object of our invention as follows: In order to support the user's ankles, the said pneumatic or roller skates are at present made with upright side stays, which extend for some seven inches, more or less, above the foot-plate and are secured to

the user's legs by side straps. These leg-supports have heretofore been rigidly fixed to or formed with the foot-plate, but according to this part of our invention we fix the two leg-supports I' I² together by cross-bars, such as I³ I⁵, (see Fig. 17,) and we joint the leg-supports I' I² to the sides of the foot-plate or horns by pins J' J², (see Figs. 1 and 2,) so as to allow of a certain movement of the user's ankles. One of these cross-bars—viz., I³—forms also the stop for the back of the wearer's heel and the other cross-bar I⁵ is higher up where the fixing-strap I⁴ is arranged. We prefer to make the two cross-bars I³ I⁵ in a piece with the leg-support I' I², as shown in Fig. 17, although, if preferred, these cross-bars may be made separate from the uprights I' I² and be riveted or otherwise suitably fixed thereto. The strap I⁴, with cross-bar I⁵ at the top of the leg-support, fits around the wearer's leg and secures the leg-supports thereto. Our improved means for securing the toe part of the foot-plate to the wearer's boots is illustrated by Figs. 1, 3, 5, and 8. We provide near the toe end of the skate a pair of side grippers L² L³, which project upwardly at l' and are adapted to grip the sole of the wearer's boot. These side grippers are continued underneath the sole-plate A of the skate and turned on a central pin m' or on two pins, preferably made as near as possible to the toe end of the skate. The side grippers L² L³ are, by the pair of links L⁴ L⁵, respectively jointed to the central sliding piece L', which is suitably guided by the pins m⁵ k⁴, fixed to the sole-plate A of the skate, and is continued backwardly toward the other end of the skate and is there connected to a coiled or other wire spring m⁷, which has a tendency to pull the slide L' backwardly and thus the grippers L² L³ toward each other to grip the wearer's boot. The said grippers are each furnished with a top part N for fastening over the toe part of the wearer's boot to firmly secure the skate thereto. On the top side of the sole-plate A there is a stop K, having its back edge k' turned up to bear against the front of the wearer's heel. This stop K can be moved to and fro and is adjusted on the foot-plate A by pins k² k⁴ on the sole-plate A, fitting in slots k³ in the stop K. By the nut k⁵ on the screw k⁶ the stop K can be cramped to the sole-plate A in any desired position. The screwing up of this nut also fixes the slide L' and the grippers L² L³ at their proper distance apart to suit the wearer's boot.

The wheels or rollers E' E² are made in any suitable manner with pneumatic or rubber-covered or soft tires to reduce vibration, and they are by preference provided with ball-bearings. We prefer to use wheels constructed as shown on our drawings, but these wheels form no part of this invention and we make no claim in respect of them. Each of the said wheels is made in halves and consists of two dished sheet-metal disks O' O², (see Figs. 1 and 2,) fixed together face to face,

as shown, by cross-bolts or by other means, and each made with an outwardly-projecting rim, so that the rims and the two disks will together form the complete rim of the wheel.

5 Each of the said disks O' O² of the wheels has raised with it an outwardly-projecting central boss, which bosses are marked, respectively, O⁷ O⁸, and each of these bosses is fitted with a steel or other metal cup for the balls of the ball-bearings, which two cups are marked, respectively, O³ O⁴, which are fitted and soldered or otherwise fixed into the central holes of the bosses O⁷ O⁸. In these cups are contained, as shown, the balls of the ball-bearings, which balls revolve on the usual coned collars fixed or otherwise secured on the wheel-axle. The wheel shown in Fig. 4 is fitted with a pneumatic tire, of which O¹² is the inner air-tube and O¹¹ is the outer india-rubber or like covering of the pneumatic tire, but we make no claim to this pneumatic tire as part of this invention.

What we claim as our invention, and desire to secure by Letters Patent, is—

25 1. In a skate the combination of a foot-plate A, an under plate H extending substantially parallel with the plate A and from front to rear of the skate, the bar L' extending longi-

tudinally between the two plates, the grippers with connections to the said bar, the spring 30 m⁷ connected to the sliding bar, said spring and grippers being arranged between the two plates, substantially as described.

2. In combination, a foot-plate, the wheels having their journals supported thereby, the 35 grippers L², L³ sliding bar L', the spring connected therewith, the heel-plate and the adjusting device consisting of the headed screw K⁴ engaging the heel-plate and the slide and the nut for setting the screw in any desired 40 position and thus adjusting the grippers, substantially as described.

3. In combination, the foot-plate, having the depending horns, a plate H secured to the bottom thereof, the horn-pieces G secured 45 to the depending horns of the foot-plate and the grippers L² L³ with means for operating the same arranged between the foot-plate and the plate H, substantially as described.

In witness whereof we have hereunto set 50 our hands in presence of two witnesses.

FRANK IORNS GIBBS.

WILLIAM WRIGHT.
